CONTAINER FOR A HAIR BRUSH

Murray Schotland, New York, N.Y.

Application December 31, 1957, Serial No. 49,086

Term of patent 14 years

(Cl. D86—10)

FIG. 1

FIG. 2

FIG. 3

FIG. 4

FIG. 5

Fig. 1 is a top plan view of a container for a hair brush showing my new design,

Fig. 2 is a side view thereof;

Fig. 3 is a left end view thereof;

Fig. 4 is a right end view thereof, and

Fig. 5 is a top plan view thereof as it appears in open position.

The dotted line illustration of the handle of a hair brush as shown in Figs. 1 and 2 is for illustrative purposes only.

I claim:

The ornamental design for a container for a hair brush, substantially as shown and described.
